United States Patent Office

Des. 185,155
Patented May 12, 1959

185,155

HANDBAG

Pascal La Grutta, Newark, N.J.

Application July 5, 1957, Serial No. 46,839

Term of patent 3½ years

(Cl. D87—3)

FIG. 1

FIG. 2

Fig. 1 is a front elevational view, the back elevational view being the same, of a handbag showing my new design;

Fig. 2 is an end elevational view.

I claim:

The ornamental design for a handbag, substantially as shown and described.
